FOREIGN PATENT DOCUMENTS

GB 2042131 9/1980

Primary Examiner—T. Chase Nelson*Assistant Examiner*—Eric L Goodman(74) *Attorney, Agent, or Firm*—Anton P. Ness; Fox Rothschild LLP(57) **CLAIM**

The ornamental design for a catheter information clip, as shown and described.

DESCRIPTION

FIG. 1 is an isometric view of a catheter information clip according to the present invention; a catheter and catheter clamp are shown in broken line for illustrative purposes only and form no part of the claimed design.

FIG. 2 is an isometric view of the catheter information clip of FIG. 1, alone.

FIG. 3 is a left side view of the catheter information clip shown in FIG. 2, the right side being a mirror image thereof; FIG. 4 is a top view of the catheter information clip shown in FIG. 2.

FIG. 5 is a bottom view of the catheter information clip shown in FIG. 2.

FIG. 6 is a proximal end view of the catheter information clip shown in FIG. 2; and,

FIG. 7 is a distal end view of the catheter information clip shown in FIG. 2.
